BED

Weronica Dry, deceased, late of New York, N. Y.,
by Louis Dry, administrator, New York, N. Y.

Refiled for abandoned application Serial No.
283,192, June 6, 1928. This application October
12, 1935, Serial No. 44,753

3 Claims.

(Cl. 5—91)

This invention relates to new and useful improvements in hospital or invalids' beds. This application is a refile of the abandoned application of Weronica Dry, Serial Number 283,192, 5 filed June 6, 1928.

An object of the invention is to provide a bed for the purpose indicated and including sections which are readily adjustable to provide for the patient using a commode without the necessity of 10 leaving the bed.

An additional object is to provide in a bed of the character indicated, compressible mattress sections and means operable from each side of the bed for drawing said sections from under the 15 patient to expose an opening below which is disposed a commode.

A further object is to provide improved cushion means for the mattress and to provide an improved sheet for use with the mattress, having 20 the sections adapted to be withdrawn from beneath the patient.

Yet another object is to provide a mattress having an improved pivoted head section and means whereby the patient may readily adjust 25 the head section to a comfortable angle and secure it there.

A further object is to provide in combination with a bed, a table or tray, carried by a bracket adjustable longitudinally of the bed on the side 30 rail thereof, and also including a table top adjustable on the tray and which, when the tray is turned to extend transversely of the bed, may be adjusted to extend across the bed for use as an eating table or the like by the patient, the tray itself being vertically adjustable and including a draw and a shelf or receptacle.

With the foregoing and other objects in view, as will become apparent as the description proceeds, the invention consists in certain novel features of construction, combination and arrangement of parts, as will be more fully described. While the drawings and following description disclose a specific embodiment of the invention, the disclosure is for the purpose of illustration 40 only and reference must therefore be had to the annexed claims for a statement of the invention.

In the drawings:—

Fig. 1 is a plan view of my improved bed including the features hereinbefore mentioned.

Fig. 2 is a longitudinal sectional view on the line 2—2 of Fig. 1;

Fig. 3 is a transverse sectional view substantially on the line 3—3 of Fig. 1;

Fig. 4 is a detail section view showing one of 55 the crushable or compressible mattress sections

and the means for supporting and manipulating the same;

Fig. 5 is a detail sectional view showing the sections withdrawn or in their position to expose the opening below which the commode is placed; 5

and

Fig. 6 is a plan view showing the improved sheet designed for use with my improved bed.

Owing to the use to which this invention is to be put, it is one of my objects to so construct the 10 bed as to be comfortable and sanitary. To this end all parts are, wherever possible, coated with white enamel, whereby they may be easily maintained in a clean and sanitary condition.

Referring in detail to the drawings, the bed includes a foot and head 10 and 11 respectively and arranged between these is a bed bottom 12 for supporting the spring, mattress and the like. Side rails 13 connect the foot and head and may be assisted by the bottom in providing a rigid frame. 20 Supported on the bottom 12 is a bed spring 14, whose center is omitted to permit of the insertion of an oval shaped spout 15 carried by a sheet 16 of thin pliable aluminum fastened to the upper middle portion of the spring.

The central portion of a mattress 17 above the spout 15 is cut away and replaced by a pair of feather stuffed inserts 18. The inserts 18 are continuous with the outer side portions of the mattress adjacent thereto as best seen in Figure 3 of the accompanying drawings. The inserts 18 may where desired be formed by making an H shaped vertical cut in an ordinary complete mattress, as for example along the solid lines bordering said inserts 18 and seen on Figure 1. When 35 constructed in this manner, it is of course necessary to finish the three free side edges of each of the inserts 18 as well as the two free edges of the mattress proper with suitable panel material. Again in Figure 5 the outer sides of said inserts 18 40 are continuous with the outer side portions of the mattress which have not yet been cut away. Since the mattress is filled with hair, felt or the like, the inserts are relatively compressible. At their inner lower edges, the inserts 18 are sewed 45 or otherwise suitably secured to movable sheets or plates 19 of aluminum of a gauge to be readily pliable or yieldable and not prevent functioning of the spring.

As clearly shown in Fig. 3 the inner ends of 50 plates 19 overlap just above the spout 15 whereby to give adequate support to the mattress at this point. The inserts fit snug with the edges of the mattress about the opening containing the inserts and the overlapping of the inner edges of plates 55

19 bring the inner edges of the plates into close relation, whereby there is no uncomfortable break in the surface of the mattress.

A commode 20 is disposed beneath the bed and 5 includes a receptacle 21 and a top 22 provided with a neck portion 23 to embrace the lower portion of spout 15. During transportation of the commode, a cover may be applied to the neck 23. When positioned as shown in Figs. 2 and 3, the 10 commode is disposed in a jar 24 on brackets 25 therein, the said jar being preferably partially filled with cold water. A strap 26 is disposed under the jar 24 and connected to each of the bed side rails 13 whereby to hold the jar and 15 commode proper in the positions shown.

At their side edges the plates 19 have secured to them pull straps 27 and these edges are also received under hooks 28 formed by turning up the outer edges of sheet 16. The hooks 28 main- 20 tain the plates in their normal position as best shown in Fig. 3 and when the patient desires to use the commode, the plates are unhooked and the straps 27 pulled in opposite directions to draw the sections 18 into the inoperative posi- 25 tions shown on an enlarged scale in Fig. 5.

To properly cover the mattress there is provided a sheet shown detached in Fig. 6. In the other views, this sheet is shown on the bed and comprises a body portion 29 having its central 30 portion cut away as in the case of the mattress. The four edges of this opening in the sheet each carry a flap and the flaps 30 and 31 are to be disposed over the edges of the opening in the mattress where the sections are not connected 35 with the mattress. Flaps 32 and 33 each carry tie strings 34 and are adapted to be disposed over the inserts with the tie strings disposed between the inserts or sections and the plates 16.

Means are also provided whereby the patient 40 may adjust the head section 35 of the mattress to suit his convenience. To this end the said head section is secured to a thin, preferably perforated sheet of aluminum 36 hingedly secured at 37 to the edge of the sheet 16. The head posts of the 45 bed carry brackets 38, the outer portions of which are shaped to rotatably receive the end portions of a roller 39 over which is disposed a strap or tape 40 secured at its lower end as at 41 to the edge of the aluminum sheet 36 and having its 50 free end disposed to be grasped by the patient to raise the head section to the desired angle.

Also supported by the brackets 38 is a rod 42 carrying intermediate its ends a hook 43 adapted to enter one of the eyes or perforations 44 in the 55 strap 40. From this it will be seen that the patient may adjust the head section to suit himself, since the hook 43 may be placed in any selected hole 44 for the purpose of securing the head section of the mattress in a comfortable 60 position.

Slidably disposed on one side rail 13 is a bracket 45 carrying at its outer end an internally threaded cylindrical portion 46 in which is adjustably disposed a threaded rod 47 on the upper end 65 of which is secured a tray 48. This tray is provided with a pair of pockets one of which may accommodate a drawer 49, while a receptacle or cuspidor 50 may be disposed in the other.

Owing to the threaded connection between the 70 rod 47 and the portion 46, the tray may obviously be turned into different positions relative to the bed. Advantage is taken of this in that a table

top 51 is provided adapted to embrace the edges of the tray as best shown in Fig. 3 and slidable on the tray as suggested by the dotted lines in Fig. 1. In the full line position of Fig. 1, the table top 51 projects beyond each end of the tray. How- 5 ever in the dotted line the bracket 45 has been moved toward the foot or bottom of the bed and the tray turned to present an edge to the side of the bed and the table top slid on the tray so as to project over the bed. This is advantageous 10 since with the table top in the position shown in dotted lines in Fig. 1, the bracket may be slid along the bed rail to position the table in front of the patient.

Owing to the use of the subject matter of this 15 invention, sanitation is important. Therefore a sanitary structure has been provided and attention is directed to the fact that the necessary parts between the spring and mattress are of metal, preferably thin pliable aluminum. Also, 20 other parts such as the tray and table top, brackets 38, roller 39 and rod 42 are all white enameled.

Having thus described the invention what is 25 claimed is:

1. In a bed, in combination, a spring having an opening therein, a mattress having a pair of sections normally disposed over said opening, a metallic sheet disposed on the spring below the mattress and having a spout extending through 30 said opening, said sheet having its edges upturned to provide hooks, plates disposed on said sheet and secured to and supporting said sections over the opening in the spring, said plates normally held in position by said hooks, and means 35 secured to said plates for drawing the same outwardly at opposite sides of the bed to displace the sections and expose the opening.

2. In a bed, the combination of a spring having a central opening therethrough, a mattress on 40 said spring, said mattress having a pair of movable sections normally disposed to fill said opening, a pair of plates connected adjacent their inner edges one to the inner edge of each of said sections and positioned one under each of said 45 sections, said plates adapted to overlap at their inner adjacent edges over the opening to support the sections in opening filling positions, and pull straps connected with the outer ends of the said plates to permit them to be drawn apart in opposite directions to move the plates and compress the sections carried thereby to expose the opening in the spring.

3. In combination, a mattress having an opening and a pair of compressible insert sections 55 adapted to fill said opening, said sections secured to the mattress at their respective opposite edges, a sheet for said mattress, said sheet including a pair of oppositely positioned flaps adapted to fold on lines extending cross-wise of the sheet and thus be disposed inward toward each other to cover opposite walls of the opening in the mattress, and a second pair of flaps adapted to fold at a right angle to the before mentioned flaps and on lines extending longitudinally of the sheet and be disposed over the adjacent edges of the sections 60 to cover said sections and to be movable therewith.

LOUIS DRY,
Administrator of the Estate of Veronica Dry, 70
Deceased.
